 The American Foundry Equipment Company,
 Mishawaka, Ind., a corporation of Delaware

Application December 4, 1935, Serial No. 52,767

8 Claims. (Cl. 51—9)

This invention relates to the treatment of metallic articles, and particularly to a combination abrasive-projector and supporting device for the articles to be treated.

In the process of abrasively-treating the surfaces of articles, such as metal castings, forgings, bars and sheets, for the purpose of cleaning, polishing or treating the articles by the abrasive effect of a stream of abrasive particles, it is desirable to support the articles in such a manner that all of the various surfaces of the articles to be treated are presented to the stream and are subjected to the effect of the abrasive stream for equal periods or for such relative periods that all of the surfaces are uniformly treated, or are each treated to the desired extent.

When the articles to be treated are of large size, irregular shape, brittle material, or otherwise difficult to handle, or are fragile, it is difficult, and in many cases impossible, to support them in a tumbling mill or other analogous arrangement for presenting the various surfaces of the articles to the stream of abrasive. It is desirable that such articles be firmly supported in a manner to prevent damage thereto, but it is also desirable that they be so supported as to present to the stream all of the sides which it is desired shall be treated.

The present invention consists in providing a combination device supporting the articles to be treated and projecting a stream of abrasive material thereagainst, which device may include an abrasive-throwing or other analogous abrasive-projecting means, together with a supporting device adapted firmly to support the articles to be cleaned and to move the articles through the stream while simultaneously turning the articles about in the stream in a predetermined manner to expose various surfaces of the articles to the impinging effect of the abrasive particles.

The supporting device suitably may consist of a conveying element such as a rotatable frame, table, conveyor or the like, mounted for movement past the abrasive-projector, and may have rotatably mounted thereon one or more table elements such as a turntable or an analogous element to support the articles to be treated. The conveying element is suitably driven to carry the table elements through the stream of abrasive, and each table element is rotated about its axis at least during the time it is passing through the stream, so as to expose the various surfaces of the articles to the stream.

The abrasive-projecting device may be designed to project a stream of abrasive having a

predetermined impingement pattern, and the supporting device may be designed to carry the table elements through the stream in such a manner that all of the articles are subjected to an equal amount of treatment. One manner of accomplishing this consists in establishing a stream of abrasive defining an elongated impingement pattern and moving the table elements through the stream along the longitudinal axis of the pattern, whereby substantially all portions of the article or articles supported on each table remain in the stream substantially the same length of time. Another method of accomplishing the desired result consists in directing the stream of abrasive angularly to the path of movement of the table elements in such a manner that the portions of each table element having the higher lineal velocities are carried through the stream a greater number of times than the slower moving portions of the table elements, in proportion to their respective lineal velocities.

A suitable housing may be provided for enclosing the stream of abrasive, and the supporting device may be positioned to carry the tables into and out of the main portion of this housing so as to permit the placing and removal of articles on the turntables when outside the main housing. The drive for rotating the turntables on the frame may be arranged so that the turntables are not rotated when in loading and unloading position, thus facilitating the placing thereon and the removal therefrom of the articles to be treated.

An object of the present invention consists in the provision of a combined abrasive-projector for projecting a stream of abrasive, and a supporting device adapted to carry the articles to be treated through the stream and to turn them about in the stream in such a manner that various surfaces are exposed to the stream and effectively treated.

Another object of the invention is the provision of a device of the class described, wherein the stream of abrasive is protectively enclosed in a housing in such a manner as to prevent undesirable scattering of the abrasive, but which housing permits ready access to the supporting device for loading and unloading purposes.

Still another object of the invention consists in the provision of a drive mechanism for turning the turntables about on the frame while they are in the stream of abrasive, and which is ineffective to rotate the tables when the tables are removed from the stream, thus facilitating placement and removal of the articles from the turntables.

Still another object of the invention consists in the provision of apparatus of the type described which is simple, rugged and compact in construction, which is rapid, efficient and effective in operation, and which may be operated substantially automatically with a minimum of supervision and with safety to the operator or attendant.

Various other features and advantages of the invention will be apparent from the following particular description and from an inspection of the accompanying drawings.

Fig. 1 is a plan view showing a device constructed according to the invention;

Fig. 2 is a front elevational view of the device shown in Fig. 1;

Fig. 3 is a vertical sectional view taken along lines 3—3 of Fig. 1;

Fig. 4 is a fragmentary view, partly in cross-section, showing the supporting mechanism proper;

Fig. 5 is a diagrammatic plan view of the supporting structure of the apparatus shown in Fig. 1;

Fig. 6 is a similar view of a modified construction;

Fig. 7 is a front elevational view of still another embodiment of the invention;

Fig. 8 is a horizontal cross-section taken along the line 8—8 of Fig. 7;

Fig. 9 is a vertical cross-section taken along the line 9—9 of Fig. 7;

Fig. 10 is a fragmentary top plan view of a portion of the structure shown in Fig. 7; and

Figs. 11 and 12 are front elevational and top plan views, respectively, showing diagrammatically certain of the structure of Fig. 1, and illustrating how the articles are treated by the stream of abrasive.

The apparatus comprises broadly a housing structure 1, on which is mounted a rotatable abrasive-throwing wheel 2, driven by a suitable driving mechanism 3, and adapted to project a stream of abrasive into the housing structure 1, and a suitable supporting device 4 rotatable within the housing and adapted to carry articles to be treated through the stream of abrasive. A conveyor system 5 collects spent abrasive from the housing, and returns it to the abrasive-throwing wheel 2 in a manner which will hereinafter be described.

Supported on a substantially cubical framework 20 constituted by suitably disposed and connected structural members, is a substantially rectangular main housing 21 having a top wall 22 and a depending hopper and collecting trough portion 60. A forwardly projecting, horizontal extension 23 formed with a vertical side wall 19 extends from the housing and is supported on the framework 20. A hood 24 extends downwardly from the top wall 22, and partially overlies the extension 23, leaving the outermost portion open. Vents 211 are provided in the top wall 22.

Mounted on the top wall 22 is a semi-circular housing 25 for the abrasive-throwing wheel 2, which housing is pivoted to the top wall 22 by means of extensions 26, rotatable on a pivot pin 27, journalled in a bearing 28. The housing 25 is maintained in closed position by a latch 29 which may be of any known construction, and which is provided with a handle 30 for releasing the latch and lifting the housing 25.

The abrasive-throwing wheel 2, preferably, is a wheel of the center-fed, centrifugal type similar to the wheel disclosed in Patent No. 1,953,566

to Peik, although any wheel of this general type may be employed. It is preferable, however, that the wheel be one adapted to directionally project a controlled stream of abrasive against the articles resting upon the moving support.

The wheel 2, preferably, comprises a plurality of blades 6 radiating outwardly from a control chamber 7. The blades may be contained within and supported by one or more rotatable side wall members or discs 8. An impeller element 9, comprising a plurality of spaced radiating vanes 10, is positioned within the control chamber and, preferably, fixed to rotate with the throwing blades 6. The abrasive is fed into the path of rotation of the impeller vanes 10, and is thrown with considerable velocity into the path of the outer throwing blades 6. A normally stationary but adjustable control member 11 of tubular form extends into the control chamber 7, and surrounds the impeller 9. The control member 11 is provided with a discharge opening 12 in the side wall thereof, of limited peripheral length, through which the abrasive is thrown by the impeller vanes 10. By adjusting the peripheral position of the discharge opening in the control member, the direction of flight of the thrown abrasive can be controlled as desired.

The wheel 2 is rotatably carried by a shaft 36 journalled in bearings 37 mounted on the top wall 22, which shaft carries a pulley 38 situated between the bearings. The pulley 38 is driven from a motor 40 which drives the shaft 41 carrying a pulley 42 over which is trained a belt 43, also trained over the pulley 38. Thus, when the motor 40 is energized, the power is transmitted to the wheel 2 to drive the same and project the abrasive against the articles.

Abrasive is fed to the wheel from a hopper 50, from which extends a conduit 51 which discharges into a smaller hopper 52. Closing the end of the conduit 51 is a pivoted closure 53 controlled by a lever 54 connected to a control rod 55 which in turn is connected to a control shaft 56. One end of the shaft is journalled in a bearing 57, and the other end in a face plate 58. A handle 59 is secured on the end of the shaft 56 for actuating the latter, and carries a pointer which cooperates with a scale on the face plate 58 for indicating the position of the closure member 53. If desired, the scale may be calibrated to indicate the volume flow to abrasive from the conduit 51.

Depending from the housing 21 is the collecting trough 60 in which is disposed a screw conveyor 61 adapted to convey abrasive from the collecting trough 60 to an elevator 62 disposed adjacent the housing 21. The elevator 62 comprises a pair of drums 63 and 64 over which is trained an endless belt 65 carrying a series of buckets 66, which conveyor is driven from a motor 67 driving a shaft 68 carrying a pulley 69. Trained over the pulley 69 is a belt 70 which is also trained over a pulley 71 carried on a shaft 72 driving the drum 64. The drum 63 at the boot end of the elevator is supported on a shaft 72' which carries a gear 73 connected by a chain 74 to a gear 75 carried on a shaft 76 extending from the screw conveyor 61. Upon energization of the motor 67, the screw conveyor 61 and elevator 62 are both driven, and the conveyor 61 delivers abrasive from the collecting trough 60 to the elevator 62 which, through the agency of the buckets 66, lifts the abrasive to the height of the hopper 50 and delivers it to the hopper 50.

Mounted on structural members 78 is a thrust

bearing 79 of the ball type, supporting a main shaft 80, which carries a table-supporting frame 81. The frame 81 comprises a square block 85 keyed to the shaft 80 and having secured to its four faces radially-extending arms 86 each adapted to support a pair of tables 87. The frame 81, tables 87 and associated members constitute the supporting device 4, referred to previously.

Each of the arms 86 may be formed at its outer end with a pair of bearing portions 88, each of which carries a pivot pin 89 pivotally supporting an arm 90, a bushing 91 being provided between the arm and the pivot pin 89. Each of the arms 90 is provided at its outer end with a pivot portion 93 in which is secured a pivot pin 94, on which is pivoted a depending cylindrical flange portion 95 of a table carrying a drum 96, a combined thrust and ball bearing 97 being provided between the pin 94 and the flange 95. The table 87, which is provided with a peripheral flange 98, is secured on the drum 96 by screws 99. Tables 87 may be replaced when worn. Threaded into the pivot portion 93 is a screw 105 carrying a roller 106 adapted to ride in the groove 107 of a track 108 supported on the inside of the housing 21. The track 108 may take the form substantially of a rectangle, hexagon or octagon of which the alternate sides are curved and the intervening sides are straight. Thus it will be seen that, as the shaft 80 is rotated, the arms 86 are carried around, and the tables 87 are moved in a generally continuous path by the arms 86. However, since the track engages the rollers 106 corresponding with each table, the axis of each table is made to follow the path defined by the track, the arms 90 swing about their respective pivots to permit the required movement of the axis of each table 87 to enable it to follow the path defined by the track 108.

The shaft 80 is driven from a motor 120 which drives a shaft 121, carrying a sprocket 122 over which is trained a chain 123 also trained over a sprocket 124 mounted on a shaft 125. The shaft 125 drives a speed-reducing mechanism which in turn drives a sprocket 127 connected by a chain 128 to a sprocket 130 carried on the shaft 80; an idler wheel 129 being provided for maintaining the tension on the chain 128.

Supported adjacent the wheel 2 is a drum 140, 50 over which is trained an endless belt 141, also trained over a drum 142 carried by a lever 143 carried by a pivot 144 secured in a bearing 145 mounted on the housing 21. The belt 141 is disposed in position, to be engaged by the peripheries of the drums 96 as they pass under the wheel 2, and to effect rotation of the drums to thereby rotate the tables while passing through the stream of abrasive.

The rotational effect of the belt on the drums may be increased by causing the belt to travel in a direction opposite to the direction of movement of the drums. This is accomplished by driving the drum 140 from a motor 150. The motor 150 drives a pulley 151 over which is trained a belt 152, also trained over a pulley 153 which latter pulley drives a speed reducer 155. The speed reducer 155 drives a sprocket 156 connected by a chain 157 to a sprocket 158 mounted on a shaft 160 which also mounts the drum 140. An idler wheel 159 is provided for tensioning the chain 157. Upon energization of the motor 150, the drum 140 is rotated to drive the belt 141 in a manner which will be apparent. The tension on 75

the belt 141 may be adjusted by adjusting the position of the lever 143 which supports the drum 142.

It will be seen that the extension 23 projects 5 beyond the main portion of the housing 21, and is provided with an open top whereby to permit access to the tables 87 as they are moved into the extension 23. The side wall of the housing 21 is provided adjacent the hood 24 with openings 170 and 171, thus permitting 10 clearance for the entrance into and exit from the housing of articles which are disposed on the tables 87. The openings 170 and 171 preferably are closed by depending curtains 172 and 173 15 which prevent the escape of abrasive from the housing 21.

Referring to Fig. 5, wherein certain essential elements of the structure of Figs. 1-4 are shown diagrammatically, it will be seen that, as 20 the shaft 80 is rotated to carry the arms 86 around and thereby move the tables 87 around in an approximately circular path, the track 108 engages the rollers 106 to guide the tables in a generally continuous path.

The articles to be cleaned are deposited on the tables 87 as the latter move along the portion *a* of their path. When each table 87 moves from the portion *d* of its path into the portion *e*, its direction is changed and the axis of each 30 table successively begins to move along in a straight line lying in a plane passing through the center line of the impingement pattern *x* of the stream of abrasive projected by the wheel 2.

Each table 87 continues to move along the 35 aforesaid straight line until the central portion of the table passes out of the stream of abrasive. Thus it will be seen that, during the time the table is moving along the straight line path *e*, all portions of the table pass through the stream 40 of abrasive substantially the same number of times. However, since the outer portions of the table are moving at a higher lineal speed than the central portions, they are not within the stream of abrasive for as long a period as the 45 central portions nearer the axis of the table. Hence the articles on the outer portions of the tables are not subject to the abrasive effect of the stream for as long a period in any one revolution as the articles in the inner portions.

This result is compensated for by the fact that the outer portions of each table enter the abrasive stream before the central portion and continue to rotate in the stream after the central portion has passed from the stream. Hence 55 the articles contained on the outer portions of the table are subjected to the effect of the stream of abrasive for a greater number of revolutions than the articles on the central portion of the table. By properly selecting the speed of travel of the table through the abrasive stream and the speed of rotation about its axis, a substantially uniform treatment of all of the articles on the several portions of the table can be effected.

In this embodiment of the invention, as well 65 as in the others disclosed herein, the stream *s* of abrasive projected by the wheel 2 spreads fanwise from the wheel, as shown diagrammatically in Fig. 11. It will be seen that the abrasive at the entrance end of the stream *s* strikes the tables 98 at a considerable angle θ to the vertical. The angle of impingement varies continuously until finally at the departure end of the stream *s* the abrasive strikes the tables 98 at a larger angle ϕ to the vertical, on the op-

posite side of the vertical from the angle θ . Since the tables 98 are continuously turned about their respective axes while in the stream, all sides of the articles q supported on the tables 98 are struck by abrasive from angles varying throughout a range corresponding to the range of angles between θ and ϕ . Hence, not only the top surfaces but all side walls and cavities, depressions and the like are subjected to the action of the abrasive, and are treated in a thorough and complete manner.

During the movement of the tables along the portion h to b of the path, they are in the extension 23 of the housing, which extension has an open top, as described above, and access may be had thereto for the purpose of depositing on the tables articles to be treated and removing articles which have been carried through the abrasive stream.

The structure disclosed in Figs. 1 to 4 may be modified slightly, as indicated diagrammatically in Fig. 6, the structural details being generally similar to those in the aforementioned figures. In this construction, a shaft 200 carries a triangular block 201 which supports three radially-extending arms 202. Pivoted to each arm at its outer end is a pair of levers 203, each of which supports a table 204, in a manner similar to that previously described, through the agency of a drum 206. Each drum 206 carries a roller 207 which cooperates with a track 208 for the purpose of guiding the tables along a predetermined generally square path, i to p , the corners g , l , n and p of which are slightly rounded to permit the rollers 207 to pass therearound.

Adjacent one side K of the track 208 is a rotating mechanism, comprising drums or rollers 209 and 210 from which is trained a belt 211. The drum 209 is suitably driven to carry the belt 211 along in a manner similar to that described in connection with the belt 141 (see Fig. 1). A similar rotating arrangement 212 is disposed adjacent the side o directly opposite the side k , and cooperates with the drums 206 in a similar manner.

Disposed above the sides k and o of the track 208 are abrasive-projecting wheels 214 and 215, respectively. These wheels may be of similar construction to the wheel 2 (see Fig. 2), and are each disposed in position to project a stream of abrasive against the upper surfaces of the tables 204 as they move along the track 208. The wheels 214 and 215 are each mounted in a position inclined relatively to the track 208 so as to project the abrasive in a stream having impingement patterns y , z , which have their longitudinal centerlines inclined to the path of movement of the tables 204.

It will be seen that, by reason of the arrangement of the wheels 214 and 215, the peripheral portions of each table pass through the stream of abrasive a greater number of times than the central portions thereof. It will also be noted that the peripheral portions of the table are moving at a greater lineal speed than the central portions, and hence pass more rapidly through the stream than the central portions. The total time during which the several portions of each table are within the stream may be made approximately equal by so positioning the wheels that the peripheral portions of the table pass through the stream a sufficient number of times so that the total time of exposure to the stream equals the time the central portions are in the stream. Thus, all portions of an article or articles sup-

ported on the tables are subjected to the same amount of abrasive treatment. It will be obvious that by varying the angle at which the wheels are disposed relative to the track, the time that any portion of a table is within the stream may be adjusted and all portions of the table may be subjected to the same amount of treatment or to any desired proportionate amount of treatment.

The provision of two wheels permits the complete treatment of all surfaces of articles during the course of a single trip around the path. The articles may be deposited on the tables 204 during their respective movements along the portion i of the path, then treated on one side during the movement along the portion k . During movement along the portion m , the articles may be turned over and then treated on the other side while moving along the portion o .

Where it is desired to treat a number of articles, all of which are the same or of generally similar shape and form, it is often desirable to provide a larger number of tables than provided in the constructions hereinbefore described, and it is often desirable to provide a separate table for each individual article. Such apparatus is especially to be desired in treating articles such as ring gears.

A construction suitable for such use is disclosed in Figs. 7 to 10 wherein the constructional details of the apparatus preferably are generally similar to those previously described, only the essential differences being expressly described and pointed out hereinafter.

A suitable housing 301 is provided, and supports on its upper wall a rotatable abrasive-throwing wheel 302 driven from a motor 304 through a driving mechanism 305. An elevator arrangement 306 is provided for conveying used abrasive from a hopper 307 at the lower portion of the housing 301 to a feed hopper 308 disposed above the wheel 302.

Mounted in a thrust bearing 309 at one end of the housing is a vertical shaft 310 carrying a drum 311, and a similar shaft 312 mounted near the opposite end of the housing supports a drum 313. Trained over the drums is an endless belt 314, to which is suitably secured a series of vertical pivot members 315, each of which supports rotatably at its upper ends a table 316 having a drum portion 317.

The ends of the shaft 312 are journaled respectively in bearings 318 and 318¹ adjustably mounted on the top wall and bottom wall respectively of the housing 301. The positions of the bearings 318 and 318¹ may be individually adjusted by adjusting mechanisms 319 and 319¹ co-operating respectively with the bearings 318 and 318¹. The tension in the belt 314 may be varied by suitable operation of the adjusting mechanisms to move the bearings 318 and 318¹, and consequently move the shaft 312 toward or away from the shaft 310.

The drum 311 is driven from a motor 317, which drives a sprocket 320 connected by a chain 321 to a second sprocket 322. The latter sprocket 322 drives a speed reducer 323 which carries a sprocket 324 connected by a chain 325 to a sprocket 326 mounted on a shaft 310. Thus, upon the energization of the motor 317, the drum 311 is rotated and moves the belt 314 in an endless elongated path.

Rotatably supported in the side wall of the housing 301 is a shaft 329 carrying a drum 330 over which is trained an endless belt 331 which

extends to and is trained over a second drum 332 mounted on a shaft 333 journalled in an adjustable bearing 334 angularly adjustable by an adjusting mechanism 335. The tension on the belt 331 can be adjusted by suitable operation of the adjusting mechanism 335.

The drum 330 is driven from a motor 340 which drives a pulley 341 over which is trained a belt 342 extending to a second pulley 343 which drives a speed reducer 344. The speed reducer 344 drives through a sprocket 345 and a chain 346 to a sprocket 347 carried on the shaft 329. Upon energization of the motor 340, the drum 330 is rotated and moves the belt 331 along a path wherein the upper length of the belt engages the drum portion 317' of each of the tables 316 which lie on one side of the endless path of the tables.

On the side of the housing opposite the abrasive wheel 302 is provided an opening 350 whereby access may be had to the tables as they pass along this side of the housing. A pair of curtains 351 and 352, a generally vertical baffle 353, slanting baffle 354 and a horizontal baffle 355 may be provided for preventing the escape of flying abrasive from the housing 301. Thus, when the tables pass along the front of the housing, access may be had to the tables for the deposit and removal of articles to be treated, without danger to the operator, and without the escape of flying abrasive from the housing.

Another baffle 356 is provided adjacent the stream of abrasive from the wheel 302, to further confine the abrasive, and baffles 357 depend from the top wall of the housing on either side of the wheel. Baffle 358 is provided above the endless belt 331 to protect the latter from the wearing effect of the abrasive particles.

Various modifications may be made in the construction of the apparatus, as will be apparent to those skilled in the art.

Since the tables are not continuously in the abrasive stream, but are moved successively into and out of the stream, the wheel or wheels need not be halted during loading and unloading, but may be operated continuously. By using a plurality of tables, articles are continuously being subjected to the stream of abrasive, and the moving stream of abrasive is thus utilized to the maximum extent.

Since the articles are disposed on and removed from the tables at a point remote from the stream of abrasive, and since the moving abrasive stream is entirely enclosed, there is no danger of the operator being injured by flying particles of abrasive. Since the tables do not individually rotate when they are in the vicinity of the opening in the housing, the articles may be handled more or less leisurely and carefully, thus greatly reducing the liability of breakage of the articles and injury to the operator from the dropping of articles due to careless or hurried handling.

The drives for the wheel, the support and the abrasive-conveyor mechanism are simple and rugged, and are of such construction that they all may be driven from separate sources of power, as shown in the illustrative embodiment. The provision of separate drives has certain advantages in that any one may be stopped, started, retarded or accelerated in accordance with operative requirements, as will be understood.

An advantage of the present invention is that it is adaptable to treat articles which have complex and irregular shapes, which require equal or predetermined, unequal exposure of various surfaces to the abrasive stream, and other types

of articles which are fragile or which cannot be treated suitably where prior types of supporting devices are employed.

Inasmuch as the tables may be made so as to be readily removable from the support, various shapes and sizes of tables may be substituted to accommodate articles of varying sizes and shapes. Although, generally, the articles will be placed upon the tables and will be retained thereon due to their own weight, yet in some instances it may be desirable to provide tables of such shape as to fit the articles to prevent shifting of the articles on the tables, or clamps may be provided to ensure that articles are retained on the tables.

While certain novel features of the invention have been disclosed and are pointed out in the annexed claims, it will be understood that various omissions, substitutions and changes may be made by those skilled in the art without departing from the spirit of the invention.

What is claimed is:

1. Apparatus for blast treating metallic articles, including in combination, means including a rotary centrifugal wheel for throwing a stream of abrasive in a divergent path having an elongated impingement pattern, a rotatable shaft, a supporting member fixed to said shaft, a table adapted to support the article to be treated, means including a swinging arm for swingably and rotatably mounting said table on said supporting member, driving means for rotating said shaft to rotate said supporting member and thereby impart a translatory movement to said table through said stream of abrasive, driving means for rotating said table about its axis during at least that portion of its translatory movement when said table is carried through said abrasive stream, and means for guiding said table during its translatory movement along a path extending generally longitudinally of the elongated axis of the impingement pattern of said stream of abrasive.

2. Apparatus for abrasively treating articles including in combination, a housing, means for projecting a stream of abrasive into said housing, a supporting frame, means for rotating said frame, a plurality of arms swingably connected to said frame, tables rotatably supported on said arms, means including a track cooperating with said arms for guiding said tables during rotation of said frame along a predetermined path extending through said housing, and means adjacent at least a portion of the path of travel of said tables for rotating the same on said arms.

3. Apparatus for abrasively treating articles including in combination, an abrasive projector for projecting a stream of abrasive, and means for carrying articles to be treated through said stream and for simultaneously moving them about in the stream, said means including a rotatably mounted frame, means for rotating said frame, a series of article supports, a track cooperating with said supports to guide them along a predetermined path, links swingably connecting said supports to said driven frame, and means for rotating each of said supports about its own axis.

4. Apparatus for treating metal articles including in combination, means for projecting a stream of treating particles, a series of supporting tables, a frame, means for rotatably mounting said frame, a track for guiding said tables along a continuous path having a portion thereof extending adjacent said stream, an arm rotatably supporting each table and swingably connected to said frame to permit said tables to follow said

continuous path, means for rotating said frame to advance said tables through said stream, and means for rotating said tables about their individual axes.

5. Apparatus for abrasively cleaning metal articles including in combination, an abrasive throwing wheel for projecting abrasive in a stream having an elongated impingement pattern, and means for conveying articles through said stream longitudinally of said impingement pattern, said conveying means including a plurality of spaced drums each mounted for rotation about a vertical axis, an endless flexible belt trained around said drums, a plurality of individual article supporting work tables, means rotatably mounting said work tables on said flexible belt, and means adjacent at least a portion of the path of movement of said flexible belt operative independently of the speed of advance of said supporting tables for rotating said individual work tables during passage through said abrasive stream.

6. Apparatus for abrasively cleaning metal articles including in combination, means for establishing a stream of abrasive, and means for conveying an article to be cleaned through said stream, said conveying means including a frame, means mounting said frame for rotation, an arm pivoted on said frame, a work holder carried by said arm adjacent the free end thereof, and means engageable with said arm adjacent the free end thereof for guiding said work holder along a non-circular path as said frame is rotated.

7. Apparatus for blast cleaning metallic objects including in combination, an abrasive throwing

wheel operative to project a fan-shaped stream of abrasive having an elongated impingement pattern, means for controlling said stream to direct the same in a downwardly direction, a rotatable frame, a plurality of article-supporting tables rotatably mounted on said frame, mechanism for rotating said frame so as to move said tables successively in a linear direction under and through the abrasive stream, mechanism operative independently of said frame moving mechanism for rotating said tables as they pass through the abrasive stream, said mechanism being operative to rotate said tables for a limited distance only during their linear travel, and means for guiding said tables along a substantially straight line during the passage of said tables through the stream.

10 15 20 25 30 35 8. Apparatus for blast cleaning articles including in combination, supporting tables for articles to be treated, means for linearly advancing said tables along a predetermined path having a straight line portion, means operative independently of the advancing speed of said supporting tables for rotating said tables during travel thereof along the straight line portion of said path, an abrasive throwing wheel for projecting a fan-shaped stream of abrasive having an elongated impingement pattern, and means rotatably mounting said abrasive-projecting wheel in a position to project the abrasive in a stream having the longitudinal axis of its impingement pattern extending in the general direction of the straight line portion of the path of advance of said tables.
